DESIGN FOR A SERVING TRAY

Simon Cantor, Brooklyn, N. Y., assignor to
La Belle Silver Co., Inc., Brooklyn, N. Y., a corporation of New York

Application January 11, 1940, Serial No. 89,387

Term of patent 7 years

To all whom it may concern:

Be it known that I, Simon Cantor, a citizen of the United States of America and a resident of Brooklyn Borough, in the county of Kings, city and State of New York, have invented a new, original, and ornamental Design for a Serving Tray, of which the following is a specification, reference being had to the accompanying drawing, forming a part thereof.

Figure 1 is a top plan view of the serving tray, Figure 2 is a side elevational view, and Figure 3 is an end elevational view with parts in section on the line 3—3 of Figure 1, showing my new design.

I claim:

The ornamental design for a serving tray, as shown.

SIMON CANTOR.
